UNITED STATES PATENT OFFICE.

COLIN CAMPBELL MCPHEE, OF CHATHAM, CANADA.

LETTER-CLIP.

SPECIFICATION forming part of Letters Patent No. 590,273, dated September 21, 1897.

Application filed February 24, 1896. Serial No. 580,601. (No model.)

To all whom it may concern:

Be it known that I, COLIN CAMPBELL MCPHEE, a subject of the Queen of Great Britain, residing in the city of Chatham, in the county of Kent, in the Province of Ontario and Dominion of Canada, have invented a new and useful Letter-Clip; and I do hereby declare that the following is a full, clear, and exact description of the same.

My invention relates to improvements in letter-clips by which a spring-plate having upturned lugs and claws bent downward, engaging with a pair of handle-bars containing and operating a traveling roller, the said spring-plate being secured to any suitable base-board for the purpose of receiving letters and holding them firmly in place and providing an easy removal of any one or all of the said letters; and the object of my improvement is, first, to facilitate the introduction of letters into the clip; secondly, to hold all letters firmly in their place that have already been inserted while successive letters are being introduced; thirdly, to admit of any one of the letters being removed without displacing the others; fourthly, this device being a self-ejector, to admit of all the letters being taken out and the ready replacement of the same, and, fifthly, to receive any width of paper. I attain these objects by the device illustrated in the accompanying drawings, in which—

Figure 1 is a side view of the device, showing position of the parts while clip is down at rest. Fig. 2 is a side view of the device, showing position of the parts when the clip is up and the roller is under pressure of the clip. Fig. 3 is a perspective view of the entire device at rest. Fig. 4 is a vertical longitudinal section showing the handle-bars reversed for the purpose of removing the letters.

Similar letters refer to similar parts throughout the several views.

The clip consists of any suitable base-board A, to one end of which is attached the spring-plate B. This spring-plate B is cut, shaped, and bent so that the two raised lugs a a are formed, as are also the two downwardly-bent claws c c, an angle being formed at the junction of the upright lugs a a and the bent claws c c. Hinged on the bar E, that is secured to the upright lugs a a at e e, are the handle-

bars d d, which are an extension of the handle D from the angle at bearings f f', the elongated spindle or axle g' engaging with the spindle g, and rotating on same is the traveling roller F. The handle D forms a loop from bearing f to f'.

The method of operating is as follows: The letter to be filed is inserted beneath the roller and passed up into the angles formed at the junction of lugs and claws, the downward pressure being put on handle D. The roller F acts as a movable fulcrum, so that the claws c c of spring-plate B are raised gradually as 65 roller and extended axle g pass forward, feeding the letter in beneath. So soon as letter has escaped the claws c c and is rolled beneath the pressure is removed from handle-bar D and all the parts revert to their former 70 position. The angle formed by the handle-bars d d and handle D is an obtuse angle, so that the spring nature of plate caused the immediate return of roller upon removal of pressure, as the bars never become perpendicular 75 to base-board. The removal of pressure upon roller which engages the letter is always concordant with the return of claws upon the letter, so that it will be readily seen that either claws or roller engage inserted letters continuously to the full extent of the spring-plate. The claws while at rest and the roller while in process of introduction form a continuous clamp, so that no matter if clip be suspended upon a wall the already-inserted 80 letters are fully and firmly held in their place without falling out while additional letters are being introduced. By reversing the motion for inserting letters and passing the handle D over the lugs a a the open ends of the handle-bars d d are brought in contact with the base-board, and as the motion is continued these ends again form another movable fulcrum, which as they go downward from top of clip gradually raise claws c c, and as these 85 bars approach an almost perpendicular position they can be allowed to remain in that position, having claws c c raised, so that any letter or letters can be selected and removed and the remaining ones reengaged by claws 90 as ends of bars d d are returned by reverse motion, or, if it is desirable to remove all the letters from beneath claws, instead of reversing this motion it can be continued until all 95 100

the letters are pushed out together by the bars *d d*.

What I claim as my invention, and desire to secure by Letters Patent, is—

5 In combination with a base-board A, and spring-plate B, having claws *c c* bent downward to receive and hold papers, and also having lugs *a a*, forming an angle with the claws *c c*, the handle-bars *d d*, pivoted to the said 10 lugs *a a*, and engaging with the roller F for

the purpose of engaging the papers as they are offered and for feeding them beneath claws *c c*, and also for holding all previously-inserted papers from dropping out during the insertion of the last paper, substantially as 15 specified and set forth.

COLIN CAMPBELL MCPHEE.
